UNITED STATES PATENT OFFICE.

JOHN KRODER, OF NEW YORK, N. Y.

CURTAIN-POLE TIP.

SPECIFICATION forming part of Letters Patent No. 298,592, dated May 13, 1884.

Application filed March 24, 1884. (No model.)

To all whom it may concern:

Be it known that I, JOHN KRODER, a citizen of the United States, and a resident of New York, county and State of New York, have 5 invented certain new and useful Improvements in Curtain-Pole Tips, of which the following is a specification.

This invention relates to tips or end pieces for curtain-poles, and has for its object the 10 production of such ornamental fixtures, so that certain parts may be changed to correspond to and be in unison with the pole to which they are applied; and it embraces the idea of supplying to the trade the tips or end pieces 15 with all their parts detached, the same being secured together and forming a completed tip when applied to the curtain-pole, leaving the arrangement and combination of the detached parts to the discretion and judgment of the 20 user.

To permit of the carrying out of this idea, the invention consists of two metal cap-pieces, and a central molding composed of one or more pieces of wood, the outer cap-piece being provided with a screw sufficiently long to pass 25 entirely through the wooden molding and the other cap-piece and into the end of the curtain-pole, thereby holding all the parts together and securely attaching the completed 30 tip to the pole. The retaining-screw may be provided with a knob and be detached from the outer cap-piece. The moldings are made of various kinds of wood or combinations of woods, from which can be selected pieces similar 35 to the kind of wood the pole is made of, or in harmony therewith. These wooden moldings fit on the central retaining-screw, and are so shaped as to be embraced by the adjacent edges of the metal cap-pieces, thus forming a 40 perfect brace to hold the cap-pieces in place when the whole is fixed to the end of the curtain-pole. The adjacent edges of the metal cap-pieces are so shaped as to interlock, so that, if desired, the wooden moldings may be dispensed with, thus forming a tip of only two 45 pieces and the retaining-screw, and entirely of metal.

In the accompanying drawings, forming part of this specification, Figure 1 represents in 50 perspective the various parts of my improved

pole-tip detached. Fig. 2 is a longitudinal section of the parts combined together and secured to the end of a pole. Fig. 3 represents a pole-tip, partly in section, in which the central wooden molding is omitted; and Fig. 4 55 shows a modification in construction.

The two cap-pieces *a* and *b* are made of metal, and preferably spun into the desired form. Their adjacent edges are shaped so that the one fits within the other or interlocks therewith, as shown at Fig. 3, and they are held together and secured to the end of the pole *c* by means of the long screw *d*, which is secured to or forms a part of the end knob, *e*. This is the simplest form in which the pieces shown 65 can be combined together to constitute a curtain-pole tip; but my invention contemplates the combination with such pieces of the wooden piece *f*. This piece *f* has a central hole, in which the screw *d* fits, and its outer 70 edges are formed into a molding of any suitable design, and it is so shaped at its sides as to be embraced by the inner adjacent edges of the cap-pieces *a* and *b*. It may be made of one piece of wood, as shown at Fig. 1, or be built 75 up of three pieces of wood, as shown at Fig. 2, *f* being the central part of one kind of wood, and *f'* *f''* outside pieces of another kind of wood; or the central part, *f*, may be made of metal or covered therewith, thus affording a 80 great variety of ornamentations from which to choose in putting the parts together to constitute tips for curtain-poles, the parts being separated, as shown at Fig. 1, when supplied to the trade, and by the user combined together, as before described.

In general I make the screw *d*, provided with the knob *e*, detached; but it may be secured to the outer cap-piece, *a*, if desired.

It will be observed that by reason of the 90 wooden molding *f*, fitting on the screw *d*, and the adjacent edges of the cap-pieces *a* and *b*, embracing the said wooden molding, the parts are firmly held together by the screw *d* when it is screwed in the end of the curtain-pole *c*, 95 and a very rigid and strong tip is produced. The inner edges of the cap-pieces *a* *b* may fit in grooves formed in the sides of the wooden molding *f*, as shown at Fig. 4.

Having now described the nature and ap- 100

plication of my improvements in curtain-pole tips, what I claim, and desire to secure by Letters Patent, is—

1. The improvement in the construction and application of curtain-pole tips which consists of the combination of two detached metal cap-pieces, a central retaining-screw, and a detached central molding composed of one or more pieces of wood, the whole secured to the end of a curtain-pole, and the tip completed by means of the retaining-screw, which is passed centrally through the other parts and screwed into the end of the pole, substantially as set forth.
- 15 2. In combination, two metal cap-pieces, a

central retaining-screw, and a wooden molding so formed as to fit on the screw and be embraced by the adjacent edges of the cap-pieces constituting a curtain-pole tip by being held together by means of the screw when 20 it is screwed in the end of the curtain-pole, substantially as hereinbefore set forth.

In witness whereof I have hereunto set my hand, at New York, county and State of New York, this 19th day of March, A. D. 1884.

JOHN KRODER.
